CLAIM

The ornamental design for an eyeglass frame tracer, as shown and described.

DESCRIPTION

FIG. 1 is a perspective view of a first embodiment of an eyeglass frame tracer showing our design;

FIG. 2 is a side view thereof;

FIG. 3 is a side view thereof taken from the side opposite to that of FIG. 2;

FIG. 4 is a front elevational view thereof;

FIG. 5 is a back elevational view thereof;

FIG. 6 is a top view thereof; and,

FIG. 7 is a bottom view thereof.

In the drawings, the solid lines depict our design.
